UNITED STATES PATENT OFFICE.

HENRY C. MILLER, OF MILWAUKEE, WISCONSIN.

DESIGN FOR A BOOK-COVER.

SPECIFICATION forming part of Design No. 33,908, dated January 15, 1901.

Application filed May 12, 1900. Serial No. 16,523. Term of patent 14 years.

To all whom it may concern:

Be it known that I, HENRY C. MILLER, of Milwaukee, in the county of Milwaukee and State of Wisconsin, have invented and produced a new and original Design for a Book-Cover, of which the following is a description, reference being had to the accompanying drawing, which is a part of this specification.

My invention has relation to a new and original design for a book-cover.

I have illustrated the design in the accompanying drawing, which shows a perspective view thereof.

As shown in the drawing, the leading or material feature of my design consists of a book-cover having the two side pieces A A and the back piece at the rear edges of the side pieces, said back piece having two longitudinal beveled edges B B and the intermediate plain flat longitudinal wide portion C.

Having described my invention, what I claim as new, and desire to secure by Letters Patent, is—

The design for a book-cover, as herein shown and described.

In testimony whereof I affix my signature in presence of two witnesses.

HENRY C. MILLER.
